United States Patent Office

Des. 221,856

Patented Sept. 14, 1971

221,856

TEST LEAD

Newil J. Kinnard, Kettering, Ohio, assignor to The National Cash Register Company, Dayton, Ohio

Filed Jan. 8, 1970, Ser. No. 20,806

Term of patent 14 years

U.S. Cl. D26—1   Int. Cl. D10—11

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a side elevation view of a test lead showing my new design, the lead wire is broken away for convenience of illustration;

FIG. 2 is a front elevational view of FIG. 1.

FIG. 3 is a top plan view of FIG. 1.

FIG. 4 is a bottom plan view of FIG. 1.

FIG. 5 is a side elevational view of a modification of my design for a test lead. The side opposite is the same as the side shown.

FIG. 6 is a front elevational view of FIG. 5.

FIG. 7 is a top plan view of FIG. 5.

FIG. 8 is a bottom plan view of FIG. 5.

FIG. 9 is a side elevational view of a further modification of my design for a test lead. The side opposite is the same as the side shown.

FIG. 10 is a front elevational view of FIG. 9.

FIG. 11 is a top plan view of FIG. 9.

FIG. 12 is a bottom plan view of FIG. 9.

I claim:

The ornamental design for a test lead, substantially as shown and described.
